United States Patent Office

Des. 188,557
Patented Aug. 9, 1960

188,557

HANDLE FOR A VESSEL OR SIMILAR ARTICLE

George H. Frost, Ashland, Ohio, assignor to Westinghouse Electric Corporation, a corporation of Pennsylvania

Filed June 22, 1959, Ser. No. 56,438

Term of patent 14 years

(Cl. D44—29)

FIG.1.

FIG.2.

FIG.3.

Fig. 1 is a perspective of a handle for a vessel or similar article, showing the new design;

Fig. 2 is a top plan; and

Fig. 3 is a side elevation.

I claim:

The ornamental design for a handle for a vessel or similar article, substantially as shown.
